[57]**CLAIM**

The ornamental design for a combined toothpaste tube container and toothbrush holder, as shown and described.

DESCRIPTION

FIG. 1 is a top, front, and left side perspective view of a combined toothpaste tube container and toothbrush holder showing my new design, the right side being a mirror image of the left, and the rear and bottom being plain and unornamented; and,

FIG. 2 is a top, front, and left side perspective view of the tube lifting element thereof, the right side being a mirror image of the left, the rear and bottom being plain and unornamented, and the housing portion being omitted for clarity of illustration.

FIG-1

FIG-2
